CLAIM

The ornamental design for a plumbing fixture base, as shown and described.

DESCRIPTION

FIG. 1 is a front perspective view of a plumbing fixture base showing our new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a cross sectional view taken on line 6—6 of FIG. 2;

FIG. 7 is a cross sectional view taken on line 7—7 of FIG. 2;

FIG. 8 is a cross sectional view taken on line 8—8 of FIG. 2; and,

FIG. 9 is a front perspective view of a second embodiment thereof.

The fragmentary broken line representations of a floor and walls in FIGS. 1 and 9 are for purposes of illustration only. The characteristic feature of our design resides in the combination of the corner ledge and the arcuate ribbed side walls adjacent thereto.
